Des. 242,578
Patented Nov. 30, 1976

242,578

COMBINED RADIO AND TELEVISION RECEIVER

Satoru Kotani, Ibaraki, Osaka, Kenichi Ito, Kawanishi, Hyogo, and Susumu Ezawa and Kiyoshi Suzuki, Ibaraki, Osaka, Japan, assignors to Matsushita Electric Industrial Co., Kadoma, Osaka, Japan

Filed Mar. 26, 1975, Ser. No. 562,333

Claims priority, application Japan Oct. 3, 1974

Term of patent 14 years

Int. Cl. D14—01, 03

U.S. Cl. D56—4 B

FIG. 1

FIG. 2

FIG. 3

FIG. 4

FIG. 1 is a front, top and right-side perspective view of a combined radio and television receiver showing our new design,

FIG. 2 is a rear, bottom and left side perspective view with the antenna in lowered position;

FIG. 3 is a top plan view thereof; and

FIG. 4 is a view similar to FIG. 1 with television receiver and antenna in lower position.

We claim:

The ornamental design for a combined radio and television receiver, as shown and described.
